DESCRIPTION

FIG. 1 is a perspective view of a support base for an electric device such as a computer, TV controller, video game machine, or audio or video disc player showing my new design, on a reduced scale;

FIG. 2 is a front elevational view thereof;

FIG. 3 is a top plan view thereof;

FIG. 4 is a rear elevational view thereof;

FIG. 5 is a left side elevational view thereof;

FIG. 6 is a right side elevational view thereof; and,

FIG. 7 is a bottom plan view thereof.
